UNITED STATES PATENT OFFICE.

ALVIS JACKSON HATHCOX, OF DURANT, OKLAHOMA.

METAL RAILWAY-TIE AND RAIL-FASTENING.

1,071,413.

Specification of Letters Patent. Patented Aug. 26, 1913.

Application filed February 13, 1913. Serial No. 748,264.

To all whom it may concern:

Be it known that I, ALVIS J. HATHCOX, a citizen of the United States, residing at Durant, in the county of Bryan and State of Oklahoma, have invented certain new and useful Improvements in Metal Railway-Ties and Rail-Fastenings; and I do declare the following to be a full, clear, and exact description of the invention, such as 10 will enable others skilled in the art to which it appertains to make and use the same.

This invention relates to improvements in metal railway ties and rail fasteners.

One object of the invention is to provide 15 a metal railway tie having improved means for supporting the rails whereby the cushioning effect produced by the usual wooden ties is retained.

Another object is to provide a railway tie 20 of this character having an improved construction and arrangement of rail fastening devices which will firmly secure the rails to the ties and will positively hold the rails against spreading or upsetting.

25 With these and other objects in view, the invention consists of certain novel features of construction, and the combination and arrangement of parts as will be more fully described and claimed.

30 In the accompanying drawings; Figure 1 is a plan view of my improved railway tie and rail fasteners; Fig. 2 is a central vertical longitudinal section thereof taken on the line 2—2 of Fig. 1; Fig. 3 is an enlarged 35 vertical cross section taken on the line 3—3 of Fig. 2; Fig. 4 is a side view of the tie and rail fastening device showing the rails in section; Fig. 5 is a detail perspective view of the lower member of the tie; Fig. 6 is a 40 similar view of the upper member thereof; Fig. 7 is a detail perspective view of one of the rail fastening devices; Fig. 8 is a similar view of one of the supporting and cushioning blocks of the rails; Fig. 9 is a similar 45 view of the wear plate employed between the cushioning blocks and the rails; Fig. 10 is a vertical cross sectional view of a modified form of the tie.

Referring more particularly to the first 50 nine figures of the drawings 1 denotes the lower or base member and 2 denotes the upper member of my improved tie. The lower member 1 is formed from a heavy metal plate having a length corresponding to the 55 length of the tie and having its edges bent inwardly or folded over onto the upper side

of the plate to form base flanges 3. The edges after forming the flanges 3 are bent upwardly at right angles to the plate to form the side flanges 4 of the lower or base member and with which the upper member 2 of the tie is engaged as will be hereinafter described. In the plate forming the base member near the ends thereof are centrally disposed longitudinal slots 5 the edges of 60 which, midway their ends, are recessed to increase the width of the slots and form enlarged passages 6 at these points for a purpose hereinafter described. The upper member 2 of the tie is also formed from a 65 heavy metal plate corresponding in length to the plate forming the lower or base member of the tie and having its side edges bent downwardly at right angles to form side flanges 7 which, when the members of the 70 tie are brought together, are engaged with the outer sides of the flanges 4 of the base member whereby said upper member is held against lateral movement on the lower or base member. The upper member 2 of the 75 tie near its ends is cut out to form openings 8 which extend a slight distance down the side flanges 7 of the member as shown at 9. The openings 8 are disposed above the slots 5 in the base member of the tie and in the 80 ends of the openings are formed centrally disposed notches or recesses 10 which align with the ends of the slots 5 in said base or lower member.

Arranged in the ends of the base member 90 1 of the tie over the central portions of the slots 5 therein are wooden rail supporting and cushioning blocks 11 which are of sufficient thickness to extend from the upper side of the base member to the lower side of 95 the top member and which have their ends beveled or inclined from the lower to the upper sides as shown. The upper surfaces of the blocks 11 when arranged between the upper and lower members of the tie are in a 100 plane above the side edges of the openings 8 in the upper member and which openings extend down into the side flanges 7 as hereinbefore described and as clearly illustrated at 9 in Fig. 5 of the drawing. With the 105 upper sides of the blocks 11 and between the same and the rails supported thereby are placed metal wear plates 12. The plates 12 when thus interposed between the rails and cushioning blocks 11 prevent the rails from 110 wearing into the blocks. It will be noted that by extending the sides of the openings 8

down into the flanges 7 of the upper tie member as shown at 9 that the plates 12 will rest entirely on the blocks 11 and do not come into engagement with the metal parts 5 of the tie, so that the full cushioning effect of the blocks 11 is obtained and imparted to the rails which rest on or engage the plates 12 as shown. In the ends of the plates 12 are formed short notches 13 which receive the bolts of the rail fastening devices hereinafter described, said bolts thus holding the plates 12 against lateral or longitudinal movement.

The rail fastening devices hereinbefore referred to comprise wedge shaped clamping members 14 which are formed of heavy sheet metal and have their side edges turned downwardly and cut at an angle to the upper portion of the plate, said downwardly turned sides forming tie and rail engaging flanges 15. The lower edges of the inner portions of the flanges 15 are recessed or notched out as shown at 16 to fit the upper side of the base flanges of the rails when the 10 fastening devices are in place on the tie. The rail fastening members when thus constructed and engaged with the tie and base flanges of the rail have their upper surfaces inclined outwardly and downwardly from 20 the opposite sides of the rails and in said upper inclined sides of the members are formed longitudinal slots 17. With the slots 17 in the fastening members and with the notches 10 in the ends of the openings 8 of the upper member of the tie and the ends 30 of the slots 5 in the lower member of the tie are engaged inclined fastening bolts 18. The upper ends of the bolts 18 project a suitable distance above the inclined surfaces of the 40 rail fastening members and have engaged therewith clamping nuts 19 which when screwed up on the ends of the bolts draw and hold the rail clamping members 14 down into tight engagement with the upper 45 side of the tie and with the base flanges of the rails and thereby clamp the latter in engagement with the ties. The bolts 18 are provided with nut locking washers 20 comprising plates having on one side a depending lug 21 to engage the notches 17 in the rail fastening members and having on their opposite sides lugs 22 which are adapted to be bent up into engagement with the adjacent side of the nuts after the latter have 55 been tightened up on the bolt and which hold the nuts against unscrewing or loosening on the bolts. The bolts 18 when arranged in the manner described are disposed at right angles to the inclined upper surfaces 60 of the rail fastening members, so that when the nuts are tightened up on the bolts, said members are drawn down squarely into engagement with the tie and flanges of the rails and the latter are prevented from 65 moving laterally in either direction. On

the lower ends of the bolts between the heads thereof and the lower sides of the base member of the tie are arranged wedge shaped spacing washers which maintain the bolts in their inclined position. The bolts when thus arranged engage the inclined ends of the cushioning blocks 11 and hold said blocks against longitudinal movement in the ties, and as hereinbefore described the engagement of the bolts with the notches 13 in the wear plates 12 also holds said plates against longitudinal or lateral movement on the blocks. By forming the recesses in the side edges of the slots 5 which provide the 70 passages 6 the headed ends of the bolts 18 may be engaged with said passages and the bolts slipped back in opposite directions into the narrower ends of the slots thereby permitting the bolts to be engaged with or removed from the base member of the tie 75 without removing the latter from its place in the ballast or bed of the road. The ends of the sections are connected by the usual or any suitable form of fish plates and the joining ends of the rail sections are engaged 80 by the inner portions of the rail fastening devices, which when clamped downwardly into engagement with the tie, securely hold the adjoining ends of the rail sections and prevent either of said ends rising above the 85 adjoining end and forming an uneven joint or becoming broken or worn off by the passage of the car wheels over the tracks. By providing the rail fastening members with the slots 17, said members may be adjusted 90 to a greater or less distance apart for engagement with rails of different widths and when adjusted and fastened by the bolts and nuts any tendency of the rail fastening members to move outwardly will cause the 95 same to be more tightly clamped against the tie and flanges of the rail by the clamping bolts and nuts thereof.

In Fig. 10 of the drawings is shown a slightly modified construction of the tie 110 wherein the base member 23 and the upper member 24 are cast or otherwise formed in one piece as shown. In forming the tie in this manner the edges of the base member are extended beyond the sides of the upper 115 portion to form base flanges 25 as clearly shown in Fig. 10 of the drawings. With the exception of forming the upper and lower members or portions of the tie integral, the same is constructed and arranged 120 and has applied thereto the same rail fastening devices as described in connection with the first form of the invention and a further description of this form of the device is not thought to be necessary.

From the foregoing description taken in connection with the accompanying drawings, the construction and operation of the invention will be readily understood without requiring a more extended explanation.

Various changes in the form, proportion and the minor details of construction may be resorted to without departing from the principle or sacrificing any of the advantages of the invention as claimed.

Having thus described my invention, what I claim is:

1. A metal railway tie comprising a lower or base member, an upper member arranged thereon and having therein near its ends openings, cushioning blocks arranged between the ends of said tie members and adapted to form cushioning supports for the rails engaged therewith, wear plates interposed between the rails and said supporting blocks, fastening members engaged with the upper side of the tie on opposite sides of the rails and with the base flanges on the latter, and clamping bolts arranged through the members of the tie and through said rail fastening members whereby the latter are secured to the tie in position for fastening the rails thereto and securing the latter against spreading or upsetting.
2. A metal railway tie comprising a lower or base member and an upper member engaged with said base member, said upper member having therein near its ends block receiving openings, rail cushioning and supporting blocks arranged between the members of the tie and engaging said openings, wear plates interposed between said blocks and rails engaged therewith, rail fastening members comprising plates bent and cut to form tie and rail flange engaging portions, and an upper outwardly inclined surface, said members having in their upper inclined sides longitudinal bolt receiving slots, fastening bolts engaged with said slots and with the upper and lower members of the

tie, clamping nuts engaged with said bolts and adapted to be screwed downwardly into engagement with said rail fastening members whereby the latter are clamped to the tie in position for fastening the rails thereto and for holding the rails against lateral spreading or upsetting movement, and nut locking washers engaged with said bolts and with the nuts and slots in said rail fastening devices whereby the nuts are held against turning on the bolts.

3. A combined railway-tie and rail fastening comprising a tie having therein bolt receiving apertures, rail fastening members comprising plates bent and notched to form tie and rail flange engaging portions, and an upwardly inclined surface, said members having in their upper inclined sides longitudinal bolt receiving slots, fastening bolts adapted to be engaged with the openings in the tie without removing the latter from the road bed, said bolts being arranged at right angles to the inclined upper surface of said fastening members, and having their ends engaged with the slots in said inclined upper surfaces, clamping nuts engaged with the upper ends of said bolts and adapted to be screwed downwardly into engagement with said rail fastening members whereby the latter are clamped to the tie in position for fastening the rails thereto and for holding the rails against lateral spreading or upsetting movement.

In testimony whereof I have hereunto set my hand in presence of two subscribing witnesses.

ALVIS JACKSON HATHCOX.
